ATTACHMENT FOR GAS BURNERS

Watson Hurlburt, River Forest, Ill.

Application August 16, 1932, Serial No. 629,013

4 Claims. (Cl. 158—116)

The invention relates to the correction of the wasteful features of gas burners as generally made today, and more particularly those on the common kitchen range, but wherever the construction is such that a similar design can be used it may be applied to a useful purpose on those burners.

When gas is burned in the open it is evident that the flame is subject to too much secondary air, that is to say, the air that contacts with the flame at the point of combustion; this does not mean that a properly mixed product has not been produced, for this should be attended to before applying my attachment.

It is common knowledge that fuel can be more economically burned in a stove than in an open fireplace. Now an ordinary gas burner is used entirely open, the same as an open fireplace. By properly enclosing the flame, while at the same time admitting only the necessary secondary air to properly promote combustion, and a desirable circulation, I am enabled to get a more efficient result from the amount of gas used. The enclosure also prevents undue blowing by air currents caused by opening of doors and the like.

I have constructed an attachment preferably of sheet metal and generally circular in form, parts of which conform to the general contour of the burner and so positioned that certain parts straddle the flame, said attachment being supported on top of the burner but in no way interfering with the egress of the gas. The peripheral ring that encloses the sides may assume a vertical or a sloping position immediately below the grate and on top of the burner itself, and may be perforated to allow entrance of the flame of a lighter—we may liken this to the sides of a shallow cup the bottom of which may have portions projecting inwardly and lying between the arms of the burner, and act as baffle plates to too much ingress of secondary air. These portions may be perforated in a variety of ways, or they may be spaced away from the openings where the gas escapes from the arms of the burner, whereby in either case the proper amount of secondary air is admitted to carry on combustion and keep up circulation.

Some burners have an almost smooth top, and anything placed thereon has no means of centering itself or retaining a proper position thereon relative to the openings for the gas. To overcome this condition I have formed lugs at the sides of the inwardly projecting portions which may be bent downwardly impinging on the body of the arms of the burner. By locating these lugs at definite distances apart circularly, I am enabled

to put on and take off my attachment as easily as placing a cover on a teapot.

The principal objects of my invention are:

1st.—That it shall correct some of the inherent defects of the present gas burners.

2nd.—To provide an attachment easily and quickly removed and replaced.

3rd.—That it may be economically manufactured.

Also other objects and advantages will be apparent as I proceed with the description.

The preferred construction as outlined in my invention I have illustrated in the accompanying drawing. Like figures refer to similar parts throughout the different illustrations.

As various deviations from that illustrated would not depart from the spirit of my invention, I do not wish to be limited to the exact details of construction herewith shown.

Fig. 1 illustrates one of my burner attachments shown in plan view, dotted lines indicating the burner itself to which the attachment is applied.

Fig. 2 is a section on line 2—2 of Fig. 1, a part of the burner itself being in section.

Fig. 3 is a section on line 3—3 of Fig. 1.

Fig. 4 is a partial plan view of my attachment adapted to a different pattern of burner than that of Fig. 1.

Fig. 5 is an enlarged section taken on line 5—5 of Fig. 4.

Fig. 6 is an enlarged section taken on line 6—6 of Fig. 4.

In the customary procedure I adjust the mixture of gas and air, if such is not already in the proper proportions. I now select an attachment wherein the openings in the horizontal members correspond in outline to the space between the burner arms, and, where depending lugs are required to center and sustain said attachment, it is dropped in place; should the lugs not conform nicely to the width of the burner arms, a slight bend, in or out, may be given them with a pair of pliers.

Many times after a very good adjustment of the mixture has been found all right, if an open flame is used, when upon seating one of my attachments in place the gas supply may be cut down without detriment to the working qualities of the burner. It is quite reasonable to expect by using my attachments a saving in gas of from 15% to 30%.

Referring to the drawing, 1 indicates my attachment. 2, a horizontal member projecting inwardly and lying intermediate of the burner arms 3, shown in dotted lines. 4 shows the

horizontal member as spaced away from the burner to allow admittance of a certain percentage of secondary air to the enclosed compartment 5. Lugs, 6, depend from the horizontal member 2, causing the opening 7 between the horizontal members 2, to straddle the jets 8 in the burner arms 3. The outside boundary of my attachment is at 9, being drawn from the same piece of metal and forming the enclosure at the sides of compartment 5. A ventilator 10, in Fig. 4 with sides 11 may be bent forward or backward, as more or less of an opening may be required to admit secondary air. Other ventilator openings as at 12, may be of a circular form having inclined edges, 13, capable of varying the size of the orifice by a more or less inclination of the enclosing walls. An opening in the member 9 may be provided for the passage of a lighter flame to contact with the issuance of gas from the jets 8, as at 14.

20 What I claim:

1. In the combination, a gas burner and an attachment designed to conserve the heat from a gas flame, said attachment having the general shape of a shallow cup forming a combustion chamber, perforations in the bottom of which allow portions of said burner to project therethrough; also perforations in said bottom to measure the influx of the secondary air to the combustion chamber.
2. In the combination, a gas burner and an attachment designed to conserve the heat from a gas flame, said attachment having the general shape of a shallow cup forming a combustion chamber, perforations in the bottom of which allow portions of said burner to project therethrough; also perforations in said bottom to measure the influx of the secondary air to the combustion chamber, the side of said attachment having openings to allow the flame of a lighter to contact the gas exuding from the burner.
3. In the combination, a gas burner made up

of a plurality of jets set off in definite groups, and an attachment having the general shape of a shallow cup forming a combustion chamber, perforations in the bottom of which allow portions of said burner to project therethrough; also perforations in said bottom to measure the influx of the secondary air to the combustion chamber, the side of said attachment having openings to allow the flame of a lighter to contact the gas exuding from the burner; the side of said attachment having horizontal members extending toward the center of the combustion space and lying between certain groups of jets, the inner ends of said horizontal members spaced away from the inner ends of opposing members, said horizontal members being in spaced relation to each other and the opposing members acting as baffle plates.

4. In the combination, a gas burner made up of a plurality of jets, set off in definite groups, and an attachment having the general shape of a shallow cup forming a combustion chamber, perforations in the bottom of which allow portions of said burner to project therethrough; also perforations in said bottom to measure the influx of the secondary air to the combustion chamber, the side of said attachment having openings to allow the flame of a lighter to contact the gas exuding from the burner; the side of said attachment having horizontal members extending toward the center of the combustion space and lying between certain groups of jets, the inner ends of said horizontal members spaced away from the inner ends of opposing members, said horizontal members being in spaced relation to each other and the opposing members, acting as baffle plates; said horizontal members equipped with downwardly extending lugs designed to impinge against the sides of said burner to keep said attachment in proper location on said burner.
